UNITED STATES PATENT OFFICE.

LEWIS A. MILLER, OF LIVE OAK, FLORIDA.

COMBINATION EVAPORATOR AND CANNING MACHINE.

1,257,725.

Specification of Letters Patent. Patented Feb. 26, 1918.

Application filed October 25, 1917. Serial No. 198,491.

To all whom it may concern:

Be it known that I, LEWIS A. MILLER, a citizen of the United States, residing at Live Oak, in the county of Suwanee and State of Florida, have invented a new and useful Combination Evaporator and Canning Machine, of which the following is a specification.

The device forming the subject matter of this application is adapted to be employed for drying fruit, vegetables and the like, in bulk, and for cooking fruit, vegetables and other products in cans.

One object of the invention is to provide a simple means whereby both of the operations specified can be carried out in a single machine.

Another object of the invention is to provide novel means whereby a proper circulation of air within the casing of the structure will be secured when the drying operation is carried out.

It is within the province of the disclosure to improve generally and to enhance the utility of devices of that type to which the present invention appertains.

With the foregoing and other objects in view which will appear as the description proceeds the invention resides in the combination and arrangement of parts and in the details of construction hereinafter described and claimed it being understood that changes in the precise embodiment of the invention herein disclosed can be made within the scope of what is claimed without departing from the spirit of the invention.

In the accompanying drawings:—

Figure 1 shows in side elevation, a device constructed in accordance with the present invention, parts being broken away and parts appearing in section;

Fig. 2 is a top plan;

Fig. 3 is a longitudinal section wherein parts appear in elevation; and

Fig. 4 is a cross section on the line 4—4 of Fig. 3, a tray, however, not disclosed in Fig. 3, having been added.

The device forming the subject matter of this application preferably is made of metal throughout and includes a cylindrical casing 1 comprising a side wall 2 and a bottom 3, the casing being supported on legs 4. A lid 5 rests on the casing and is supplied with a

marginal flange 6 surrounding the casing. The lid 5 and its flange 6 are provided with 55 peripheral notches 7. Handles 8 may be mounted on the lid 5.

A drum 9 is mounted in the bottom 3, the bottom being closed at the top and open at the bottom. L-shaped flues 10 are provided, 60 the inner, lower ends of the flues opening through the side wall of the drum 9, the flues extending outwardly, parallel to the bottom 3, and thence extending upwardly, along the inner surface of the casing 2, 65 through the notches 7 in the lid 5. There may be any desired number of these flues 10. Air inlet tubes 11 are mounted in the casing 1 near to the bottom 3, and parallel thereto. The air inlet tubes 11 are radially 70 disposed with respect to the axis of the casing 1 and the drum 9. The inner ends of the air inlet tubes 11 terminate close to the periphery of the drum 9, but in spaced relation thereto. The outer ends of the tubes 75 11 are closed by any suitable means, such as plugs 12, which may be connected to the casing 1 by means of flexible elements 14.

The numeral 15 denotes a heater which may be of any desired form, depending upon 80 whether a solid fuel, a liquid fuel or a gaseous fuel is to be used. In the present instance, the heater is shown in the form of a receptacle, connected at its upper end with the bottom 3 and surrounding the lower end 85 of the drum 9, the drum opening into the receptacle. The heater 15 may include a stoke door 16, an ash door 17 and a grate 18.

Disposed within the casing 1 and secured thereto are supports 19, of which there may 90 be any desired number. The supports 19 are adapted to uphold a tray T comprising a peripheral frame 20 and a body 22, the latter being made of wire netting, if desired.

The frame 20 is provided with recesses 95 23, adapted to receive the flues 10, when the tray is mounted on the supports 19.

If desired, a tray 24 may be used, the same having a perforated bottom 25. Hangers 26 are connected with the tray 24, and 100 are supplied at their upper ends with laterally extended loops 27, adapted to engage over the upper ends of the flues 10, in the notches 7 of the lid 5.

If the structure hereinbefore described is 105 to be used for drying or evaporating vege-

tables and like products, then any desired number of the trays T shown in Fig. 4 are mounted on the supports 19. The plugs 12 are withdrawn from the inlet tubes 11. 5 The products of combustion emanating from the heater 15 pass upwardly into the drum 9 and pass, thence, laterally, through the lower ends of the flues 10, and upwardly through the vertical portions of the flues, an even distribution of the heat being secured in this way. Air enters the casing 1 by way of the inlet tubes 11 and is discharged close to or against the drum 9, which is highly heated. The air is heated by contact with the drum and is also heated, as it passes upwardly, by the flues 10, the air leaving through the notches 7 in the lid 5.

If the structure is to be used for canning, then the plugs 12 are mounted in the tubes 20 11 and the casing 1 is filled to any desired extent with water, the tray 24 being suspended on the upper ends of the flues 10 by means of the hangers 26 and the loops 27. The water in the casing 1 may be boiled, about the canned material on the tray 24. 25 When the canning operation has been concluded, the plugs 12 may be pulled out of the tubes 11, thus permitting the water to be drained off.

Copies of this patent may be obtained for five cents each, by addressing the "Commissioner of Patents, Washington, D. C."

Having thus described the invention, what is claimed is:—

1. In a device of the class described, a casing comprising a bottom; a lid on the casing; a heater connected with the bottom and located there below; a drum opening 35 through the bottom into the heater; flues extended outwardly from the drum and upwardly along the inner surface of the casing through the lid; inlets opening through the casing adjacent the bottom and terminating 40 at their inner ends adjacent the drum; means for opening and closing the inlets; a tray; and means for supporting the tray in the drum.

2. A device of the class described constructed as described in claim 1, and further characterized by the fact that the means for supporting the tray consist of hangers provided at their upper ends with means for engaging the upper ends of the flues detachably. 45

In testimony that I claim the foregoing as my own, I have hereto affixed my signature in the presence of two witnesses.

LEWIS A. MILLER.
